EUGÈNE LECOCQ, OF BRUSSELS, BELGIUM, ASSIGNOR TO SOCIÉTÉ GÉNÉRALE DE FOURS À COKE, SYSTEMES LECOCQ (SOCIETE ANONYME), OF BRUSSELS, BELGIUM.

REGENERATIVE COKE-OVEN.

1,199,996.

Specification of Letters Patent.

Patented Oct. 3, 1916.

Application filed August 26, 1913. Serial No. 786,650.

To all whom it may concern:

Be it known that I, EUGÈNE LECOCQ, a subject of the King of Belgium, civil engineer, residing at Brussels, in the Kingdom of Belgium, have invented certain new and useful Improvements in Regenerative Coke-Ovens, of which the following is a specification.

The present invention has for its object 10 a regenerative coke oven permitting the simultaneous heating of the air and the combustible gas and their distribution in the chambers with a view of utilizing, for the heating of the oven, gas from blast furnaces or other gas of low heating power.

It has long been known, and was applied in the first place by Siemens, that to obtain high temperatures by the use of gas of low calorific value, it is necessary to previously heat at the same time the air and the gas. In the common forms of regenerative coke ovens, such as are usually employed, *i. e.* those heated by the gas from the coke oven, the air alone is previously heated and these furnaces as generally hitherto constructed do not allow of the simultaneous heating of the air and gas. It is true that certain constructions have been proposed in which one part of the regenerator is used for the heating of the air while the other part can be used for the heating of the gas by providing the oven not only with a direct arrival of the gas but moreover with special junction to certain parts of the divided regenerators. These arrangements however present complications and serious difficulties from the point of view of regulating the gas and air in each chamber.

40 The arrangement forming the object of the present invention has for its end the permitting of the heating of the gas and the air by means of regenerators for the air and regenerators for the gas and assuring by practical and simple means the distribution of the air and gas in each chamber and the independent regulation of the air and gas in each chamber. For this purpose each oven is provided with four channels, under the hearth, separate throughout their length and connected to the regenerators in such a way that two adjacent

channels are traversed by the air and the two other adjacent channels by the combustible gas, while the series of the four channels of the adjacent oven is traversed by the burnt gases.

Figure 1 is a longitudinal section of an oven and shows on the left hand side a section taken on line A B and on the right hand side a section taken on line B N of Fig. 2. Fig. 2 is a vertical section taken on the left hand side on line G H and on the right hand side I—J of Fig. 1. Fig. 3 is a horizontal section the upper half being taken on line E—F Fig. 2 and the lower part on line C—D, Fig. 1. Fig. 4 is a section taken on line A B Fig. 2 of the drawing, said section being taken throughout the whole length of the oven; Fig. 5 is a section on line B N of Fig. 2, taken also throughout the whole length of the oven; Fig. 6 is a detail of the section corresponding to Fig. 2, but drawn on an enlarged scale in order to show all the ducts or openings between the heating walls and the channels *k l m n*; and Fig 7 is a horizontal section through line E F (Fig 2) but taken on the whole length of the ovens.

The general arrangement of the oven in so far as it relates to the construction of the structure is similar to that shown in my former application Serial No. 765972 and consists of a battery of regenerators for each oven, comprising a pair of groups of regenerators situated at opposite ends of the oven, which regenerators have been designated *g*. Each group of regenerators is distinct and separate, the groups at the opposite ends of the ovens being separated by a wall *g'*, while the regenerators of each group are preferably formed with a vertical axis by constructing longitudinal walls 9, which are connected by transverse or cross walls 10 (see Fig. 3). As will be clear from Fig. 2 of the drawings there is associated with each oven a battery of such regenerators which have been designated from 1 to 8, in this view. Positioned directly above the regenerators are the ovens, three of such being designated 11, 12 and 13 in the various views and positioned between these oven are the heating chambers 14 and 15. The combustible gas arrives al-

ternately by the conduits *a b* (Fig. 1) situated at the front and back of the ovens. To permit the heating of the gas these conduits are connected to one half of the regenerators by a pipe provided with a tap *c* and a damper *d*. Also for example the conduits *a b* are connected to two sides of the uneven numbered regenerators 1, 3, 5, 7, etc., while the even numbered regenerators 2, 4, 6, 8, etc., are directly connected to the collecting galleries *e f* without being able to communicate with the gas inlet conduits. When the dampers *d* are raised the odd numbered regenerators are connected directly with the collecting gallery while when they are lowered they cut off these regenerators from the collecting gallery and connect them to the gas inlet conduits *a b*. Each regenerator *g* situated in the central part of the battery is provided with a channel *h i* communicating with two adjacent channels under the hearth so arranged that each oven has four corresponding channels *k l m n* under the hearth separated from each other and in which the entrance of the gas or air can be regulated by the dampers *p*.

The action of the oven is as follows: During one period of working the air enters for example by the collecting gallery *f* and passes directly to the even numbered regenerators *g* (2, 4, 6, 8, etc.) permanently connected to the collecting gallery. The dampers *d* situated on this side are lowered so as to put the conduit *a* in communication with the odd numbered regenerators. The dampers *d* situated on the opposite side are on the contrary raised to connect all the regenerators situated on this side with the collecting gallery *e*. The air traverses the even numbered regenerators and the gas traverses the odd numbered regenerators and through the communicating conduits *h* the air and the gas are conducted to the separate channels *k l m n* under the hearth of a given oven, which distribute them to the adjacent chambers of the oven. The burnt gases return through the channels underneath the hearth of the adjacent ovens to give up their heat to the regenerators situated at the other side of the battery; thence they pass through the collecting gallery *e* and the reversing apparatus and finally escape in the chimney. Referring more specifically to the manner in which the air and gas are conducted to and away from the heating chambers, and assuming that, for example, the air comes by the flue *f* into the regenerators 2, 4, 6 and 8 and that the gas enters by the gas inlet conduit *a* into the regenerators 1, 3, 5 and 7 on the lefthand side of the oven, as viewed in Figs. 1 and 4, the air from the regenerator 6 passes through the passage *h* into the channels *k l*, and is distributed through the conduits 16 and 17

(the latter being shown in dotted lines in Fig. 6) into the two heating chambers 14 and 15 adjacent the oven 11, while the gas from the regenerator 5 passes through the conduit *h* into the sole channels *m n*, and is distributed into the same heating chambers 14 and 15 through the conduits 18 and 19, the latter of which is shown in dotted lines in Fig. 6. The mixture of air and gas, therefore, takes place in each of the compartments 10' formed in the heating chambers (see Figs. 1, 4 and 5), which chambers are serially arranged the whole length of the oven. After the combustion takes place in these chambers the gases of combustion then descend through the adjacent chambers 11', and return through the conduits 22 and 29 from the heating chamber 15, into the sole channels *l' n'*, positioned beneath the adjacent oven 12, while the burnt gases from the heating chamber 14 return through the openings 21 and 28 into the sole channels *k' m'* positioned under the oven 13. The four channels *k' l' m' n'*, are, therefore, subsequently traversed by the burned gases which pass through the conduits *i* (see Fig. 5) into the regenerators 5 and 6 positioned on the righthand side of the oven, and then to the collecting flue *e*. As will be clear from Fig. 7 adjacent sets of sole channels are connected to the regenerators at opposite ends of the oven so that by using the reversing apparatus in the manner described, it is possible to reverse the flow of air and gas through the sole channels and the various other portions of the regenerators and heating chambers. In the next period the positions of the dampers *d* situated at each side of the oven are reversed and the travel of the gas and of the air and also of the burned gases are similar but in the opposite direction. It will be seen in this arrangement that the channels under the hearth of each oven are four in number and are separate for the whole of their length, and that two adjacent channels *k l* (Fig. 3) of one oven are traversed by the air and the other two *m n* by the combustible gas while all the four channels *k l m n* of the adjacent furnace are traversed by the burnt gas. These channels are designated by *k' l' m' n'* in Figs. 3 and 6. Considering this arrangement and the fact that two adjacent channels under the hearth both traversed by the combustible gas or by the air, are connected by a single conduit *h i* to the same regenerator *g* the damper *p* can be used to regulate separately the quantity of gas or air in each channel under the hearth. The conduits *h i* can be of any desired form and connect the regenerators to the channels under the hearth at any point, i. e. either at the center or at the ends.

The air regenerators or the gas regener-

ators may be completely independent of each other or can be isolated one from the other without the one affecting the other.

What I claim is:

5. 1. In a regenerative coke oven, in combination with each oven and its heating chamber, four separate sole channels provided under the hearth of each oven, and means including regenerators for supplying
10 two of said sole channels with gas and two with air or for connecting all four of said channels to convey the burnt gases from the heating chambers.

2. In a regenerative coke oven, in combination a plurality of ovens, a heating chamber adjacent to each of said ovens, two groups of regenerators for each of said ovens, four separate channels arranged under the hearth of each of said ovens, conduits connecting said channels in pairs with a group of regenerators, and distributing conduits connecting the said channels to two adjacent heating chambers of the ovens.

3. In a regenerative coke oven, in combination a plurality of ovens, a heating chamber adjacent each oven, two groups of regenerators for each oven, four separate sole channels arranged under the hearth of each oven, conduits connecting said channels in pairs to adjacent groups of regenerators, the adjacent sets of channels being connected to groups of regenerators on opposite sides of the oven, and distributing conduits connecting said channels to two adjacent heating chambers of the oven.

4. In a regenerative coke oven, in combination a plurality of ovens, a heating chamber adjacent each oven, four separate sole channels arranged under the hearth of each oven said channels being separate throughout their length, a group of regenerators at opposite ends of each oven, conduits connecting the sole channels in pairs to adjacent groups of regenerators at the same end of
45 the oven, adjacent sets of channels being con-

nected to the regenerators at opposite ends of the oven, gas inlet conduits and collecting galleries adjacent the groups of regenerators at each end of the oven, means for connecting alternate groups of regenerators 50 at each end of the oven alternately to the gas conduits and collecting galleries, and means for connecting the remaining groups of regenerators at each end of the oven to the collecting galleries.

5. In a regenerative coke oven, in combination a plurality of ovens, a heating chamber adjacent to each of said ovens, four separate channels arranged under the hearth of each of said ovens, distributing conduits 60 connecting said channels to two adjacent heating chambers, the first and the third of said channels being connected by said distributing conduits to the heating chamber of a given oven and the 2d and 4th of 65 said channels being connected by said distributing conduits to the heating chamber of the adjacent oven, groups of regenerators situated on each side, under the ovens and heating chambers, the regenerators situated on the same side comprising alternately gas regenerators and air regenerators, a conduit connecting each of the said gas and air regenerators to a pair of the channels under the hearth of each oven, dampers coöperat- 70 ing with each of said conduits, whereby the quantity of gas or of air in each pair of channels under the hearth can be regulated separately gas inlet conduits, collecting galleries adjacent to the groups of regen- 75 erators, means whereby the air regenerators of each group are permanently connected to the adjacent collecting gallery and means whereby the gas regenerators of each group can be connected either to the 80 collecting gallery or to the gas inlet conduits.

In testimony whereof I have affixed my signature.

EUGÈNE LECOCQ.
